CLAIM

The ornamental design for a coin telephone set enclosure, substantially as shown and described.

DESCRIPTION

FIG. 1 is a front perspective view of a coin telephone set enclosure showing our new design;

FIG. 2 is a top plan view thereof;

FIG. 3 is a right side elevation view thereof; and

FIG. 4 is a bottom plan view thereof.

The broken lines representing the telephone structure are shown for purposes of illustration only.

FIG. 3

FIG. 2

FIG. 4
